KEY PUNCH

Lester L. Curtis, Newark, N. J., assignor to The
McBee Company, Athens, Ohio, a corporation
of Ohio

Application January 18, 1947, Serial No. 722,790

20 Claims. (Cl. 164—112)

1

The present invention relates to key operated card punching machines, and more particularly to machines for notching perforated cards along their marginal areas.

In the notching of cards having rows of holes along their marginal areas, an objectionable sliver or tab of card stock remains when adjacent holes are notched out by devices heretofore employed. Accordingly, it is an object of the present invention to provide an apparatus for notching adjacent holes in cards without allowing intervening stock to remain.

A further object of the invention is to provide a keypunch machine in which the number of punches required to perform the complete card punching operation is considerably reduced.

Still a further object of the invention is to provide a punch arrangement for notching perforated cards in which the individual punches have a greater width than heretofore employed.

Another object of the invention is to provide an improved key operated punching machine of simpler construction than heretofore provided, in which the number of operating parts for performing the punching operation is substantially reduced.

In its general aspects, the invention contemplates a plurality of individual die blocks and associated punches, in which the punches are arranged to notch intermediate or alternate perforations along the marginal areas of a single or multiple row of holes in a card or check. Each punch has a width equal to or slightly greater than the pitch or spacing distance of the holes in the card marginal areas. Only about one-half the number of punches heretofore required for perforating the entire series of fields along the card margins is required, since the punches operate on only alternate perforations during their actuation toward the die portion of the apparatus. Following such perforations, the punches are shifted along the marginal edge of the card a distance equal to the pitch between the perforations or holes in the margins of the card and another punching actuation takes place. By virtue of this arrangement, the punches may be made of a width equal to or slightly greater than the pitch spacing distance between the card perforations, thus eliminating the sliver or tab of card stock that would remain between adjacent perforated holes punched simultaneously by parallel punches.

The machine is designed for operating a plurality of individual die blocks and associated punches during the cycle of operation of the card, the notching being preselected by the de-

2

pression of keys in a full keyboard bank prior to actuation of the apparatus to effect movement of the punches toward their female die member. The keyboard and its associated mechanism are so constructed and arranged as to cause certain of the punches to produce either a shallow notch to the first row of perforations in cards having multiple rows of holes or a deep notch therein, as required.

10. One form which the invention may assume is exemplified in the following description and illustrated by way of example in the accompanying drawings, in which:

Fig. 1 is a top plan view of a machine for punching cards having rows of holes along their marginal areas, portions of the outer housing or covering having been removed to disclose the interior mechanism.

Fig. 2 is a side elevation of the machine, disclosing the interior mechanism, as viewed along the line 2—2 of Fig. 1.

Fig. 3 is a longitudinal section taken generally along the line 3—3 on Fig. 1, disclosing the punch actuating mechanism.

20. Fig. 4 is a partial longitudinal section taken generally along the line 4—4 on Fig. 1, disclosing part of the key latching mechanism.

Fig. 5 is a partial section taken along the line 5—5 on Fig. 1, disclosing the main shaft actuating portion of the device.

Fig. 6 is a partial cross-section taken along the line 6—6 on Fig. 2, disclosing the arrangement of the slideable horizontal selector members.

Fig. 7 is a somewhat diagrammatic representation of the horizontal selector punches and card to be notched, with the punches illustrated in one position with respect to the selector members and card.

Fig. 8 is a view similar to Fig. 7, disclosing the punches shifted along the edge of the card and along the selector members a distance equal to the pitch between adjacent card perforations.

Fig. 9 is a partial plan view of a notched card.

Fig. 10 is a diagrammatic view representing the time relationships of the different parts of the mechanism during a complete cycle of its operation.

50. In the machine disclosed in the drawing, a punch and die mechanism is provided for selectively notching the marginal areas of cards from the outer edge of the card to either an outer or inner row of perforations. In one type of perforated card, the marginal areas are divided into fields, each field being adapted to be punched to one or more of its perforations to indicate a particular number. As an example, the card

55

10 illustrated in Fig. 9, and adapted for use in the full keyboard machine illustrated in the drawings, contains ten fields 11 along its longitudinal marginal portion, each field having outer and inner rows 12, 13 of perforations. Although various arrangements of such perforations may be made, particular reference will be made to the card shown in Figs. 7, 8 and 9, in which the outer or shallow perforations 12 are representative of the numbers "1," "2" and "4," and a single inner perforation 13, representing the number "7," is placed in alignment with the number "4" perforation on a line perpendicular to the longitudinal edge of the card.

By making a shallow notch from the edge of the card to the number "1," "2" or "4" perforation, the corresponding number on the card is indicated. By making a deep notch in the card to the number "7" perforation, such corresponding number is indicated. Number "3" is notched in the card by notching both the number "1" and number "2" perforations; number "5" by notching the number "1" and number "4" perforations; and number "6" is obtained by notching the number "2" and number "4" perforations. Number "8" is obtained by notching the number "1" and number "7" perforations, and number "9" is obtained by notching the number "2" and number "7" perforations. If no notching is performed in any particular field, that fact indicates the number "0."

The machine includes an outer housing 14 and a base 15 from which extends a pair of spaced vertical arranged side frames 16, 17. The forward portion of the housing is generally horizontal and constitutes a table 18 on which a card 10 to be punched may be placed, the inner marginal area of the card extending within the housing for reception between the female die blocks 19, having slots 20 arranged vertically or perpendicular to the edge of the card, and cooperable punches 21 which are pivotally mounted on the die blocks, as by pins 22 extending through the upwardly extending die block ears 23 and the lower rear portions of the punches. By pivotal movement about its pivot pin 22 in a downward direction, each punch 21 is brought into and out of cooperative relation with the associated cavity 20 in the die block 19.

The die blocks 19 and the punches 21 disposed thereabove are individually movable in a direction perpendicular to the edge of the card 10. When disposed in full forward position over the card, a punch is in position for cutting a deep notch to the inner number "7" perforation. When positioned in an intermediate location with respect to the card, the punch will cut a shallow notch at either the number "1," number "2" or number "4" perforation, and when disposed in a fully rearward position, the punch 21 will move clear of the card and will not effect any notching at all during its movement toward the female die cavity 20.

The punches are alternately arranged with respect to the perforations in the card. That is, punching can only be effected at alternate perforations or holes along the marginal area of the cards during downward actuation of the punches 21 toward the die block cavities 20. The punches and dies are mounted for sliding movement in a carriage 24 extending transversely across the machine and having one extension 25 slidably mounted in one of the side frames 17 and a second extension 26 slidably mounted in the other side frame 16, extending outwardly therefrom.

5 The entire carriage is shiftable transversely in order to shift the punches 21 and dies 19 a distance equal to the center to center distance between adjacent perforations 12 along the margins of the card as described hereinafter.

10 The carriage 24 is provided with forward and rearward uprights 27, 28 on which the punch and die blocks 19 are slidably supported. Each die block has a forward extension 29 projecting through a slot 30 in the forward carriage upright 27, and also a rearward extension 31 extending through a slot 32 in the rear carriage upright 28. Each die block and punch is urged in a rearward direction by a spring 33 having one end secured to a suitable pin 34 on the carriage 24 and its other end attached to the die block itself.

15 The extent of rearward movement of each die block 19 is determined by engagement of its rearward extension 31 with an aligned lug 36 whose position is selected in accordance with the depression of a key 37 on the keyboard. The lug 36 may occupy a position indicated by the dotted line C (Figs. 2, 7 and 8), which allows the spring 20 33 to move the associated die block 19 and punch 21 to its fullest rear position and place the associated punch completely out of disposition over the card 10, so that its downward actuation cannot effect notching of the card. The lug 36 may 25 be moved forwardly to an intermediate position indicated by the dotted line B, in which the punch extends over an outer perforation 12 to effect a notching of either the number "1," "2" or "4" perforation, or the lug may be positioned forwardly to coincide with the dotted line A position, 30 in which the punch 21 is disposed forwardly to notch deeply over the number "7" perforation. In all instances the springs 33 tend to move the die blocks 19 and punches 21 to their full rearward positions; their forward movement against the spring actions being produced by a transverse bar 38 engageable with the rear sides of the forward die block extensions 29.

35 Positioning of the lugs 36 and slidable die blocks 19 and punches 21 are determined selectively by appropriate depressions of the keys 37 in the keyboard. As disclosed in the drawings, there are ten columns of depressible keys, each column of keys having numbers ranging from "1" to "9" along the inclined housing face. Depression of each key effects a corresponding positioning of the lugs 36 and determines the extent of rearward movement of the die blocks 19 and punches 21, thereby appropriately disposing the 40 die blocks and punches with respect to the card 10 placed on the table 18. Each key 37 forms the upper part of a key stem 39 movable vertically within the machine frame and having one or more inclined cam surfaces 40 adapted to cooperate with one or more horizontal sliding selector members 41 on whose forward ends the lugs 36 are provided. The sliding members are guided for movement within the frame of the machine by appropriate guide pins 42 extending through 45 horizontal slots 43 in the forward and rear portions of each sliding selector member. Rearward movement of each selector member 41 is accomplished by a spring 44 attached to the machine frame and to the rear of the sliding member, while its forward movement is determined by depression of a key 37, which will cause its inclined cam surface 40 to engage a follower pin 45 on the sliding member and move the latter in a forward direction.

50 In a specific machine disclosed, which is de-

signed to operate on cards having the "1," "2," "4" or "7" perforations, each column of keys is designed to control three horizontal sliding members 41a, 41b, 41c disposed one above the other, but with their lugs 36 in side by side horizontal alignment. Thus, the uppermost sliding member 41a has its forward lug 36a designed to cooperate with a punch 21 and die 19 for notching the number "1" perforation; the intermediate sliding member 41b is adapted to position its lug 36b and the associated die and punch for notching the number "2" perforation; and the lowermost sliding member 41c is designed to position its lug 36c and an associated punch and die for notching either the number "4" or number "7" perforation. Accordingly, the number "1" key stem 39 in each column of the ten bank keyboard has a cam surface 40 cooperable with a follower pin 45 on the uppermost slide 41a; the number "2" key stem has a cam 40 engageable with a follower pin 45 on the intermediate slide 41b for effecting the notching of the number "2" perforation; the number "4" key stem has a cam 40 engageable with a follower pin 45 on the lowermost slide 41c for effecting a shallow notch to the number "4" perforation on the card; while the number "7" key stem has a cam surface 40a with a flatter inclination adapted to operate on a follower pin 45 and move the lowermost slide 41c and its forwardly extending lug 36c a greater distance upon depression of the "7" key, to position its lug 36c and the die block and punch assembly 19, 21 for effecting a deep notch to the member "7" perforation.

Similarly, the number "3" key stem has cam surfaces 40 cooperable with follower pins on both the number "1" and "2" sliding members 41a, 41b; the number "5" key stem has cams engageable with pins on both the upper number "1" and lower "4" slides 41a, 41c; and the number "6" key stem has cams engageable with pins for actuating both the number "2" and number "4" slides 41b, 41c. In addition, the number "8" key stem has cams 40, 40a engageable with pins 45 for actuating both the upper number "1" slide 41a and the lower number "7" slide 41c, its lower cam surface 40a being inclined to the same extent as the cam surface on the number "7" key; while the cams on the number "9" key stem operate on pins on both the number "2" slide 41b and the number "7" slide 41c. Depending upon the depression of the key 37 in a particular column, the lugs 36 on the forward portions of the slides 41 are appropriately positioned, being moved to either the A, B or C position (Figs. 2, 7 and 8), and controlling the extent of rearward movement of an associated die block extension 31 under the influence of its spring 33.

The keys 37 are held in their depressed position by a latch mechanism. Each key stem 39 in a column has a laterally extending pin 46 adapted to engage against an inclined cam surface 47 on a lock slide 48 mounted for forward and rearward movement along the frame by forward and rearward guide pins 49 secured to the frame and extending through slots 50 in the latch or lock slide 48. The depressed key stem 39 causes its pin 46 to engage against the cam surface 47 and move the slide rearwardly, which permits the pin 46 to move off the cam portion of the slide and the slide body itself. Following such entry, a spring 52 secured to the frame and slide 48 moves the latter forwardly to dispose its cam 47 over the pin 46 and prevent ele-

vation of the key stem 39 until the slide 48 is again moved rearwardly.

The depressed keys 37 are held in their lower position against the action of return springs 53, attached to the cover of the machine and to the key stems 39, by engagement of the cams 47 over the pins 46, holding the latter in the latch recesses 51, rearward movement of the lock slides 48 effecting release of the stems 39 and permitting their elevation by the return springs 53. Such rearward movement takes place by shifting a bail 54 extending transversely across all of the lock slides 48 and forwardly of upward projections 55 at the rear of the slides. The bail 54 is carried between two lever arms 56 mounted on a shaft 57 journalled in the side frame members 16, 17, the free end of one of the lever arms 56 being connected to a link 58 extending forwardly of the machine and urged in such forward direction by a spring 59 attached to the link and to the machine frame (see Fig. 4). The forward portion of the link has a lug recess 60 adapted to be engaged by a stud 61 secured to a disk 62 fixed to the main shaft 63 of the machine. This stud 61 is also adapted to engage a cam surface 64 on the underside of the link. Rotation of the shaft 63 and disk 62 in a forward direction has no effect on shifting the bail shaft 57 rearwardly. However, return rotation of the main shaft carries the disk 62 in a counter-clockwise direction (as seen in Fig. 4) and engages the stud 61 in the recess 60 on the link 58, shifting the latter rearwardly and causing the bail 54 to move all of the lock slides 48 rearwardly to free them from the key stem pins 46 and allowing the return springs 53 to re-elevate the stems 39.

Following release of the key stems 39 and as the link 58 continues its rearward movement, a cam surface on a cam projection 65 of the link 40 engages a stationary stud 66 attached to the side frame, causing the link 58 to be elevated to remove the lug recess 60 completely from engagement by the disk stud 61, allowing the spring 59 to again move the link forwardly and place the bail 54 and the lock slides 48 in their forward positions, in which the depressed key stems 39 can again be locked.

During the cycle of operation of the machine, all die blocks 19 and the punches 21 pivoted thereon are moved in a forward direction by the transverse bar 38 engaging the rear portions of the forward die block extensions 29. This bar is then moved rearwardly to permit engagement of the rearward die block extensions 31 with aligned lugs 36 on the horizontal selector members 41. Movement of the bar 38 is determined by motion of the main shaft 63.

The bar 38 is secured to a pair of spaced arms 67 attached to a shaft 68 journalled in the side frames 16, 17 of the machine. One of the arms is connected, by a rod or link 69, to another lever arm 70 oscillatable on a shaft 71 extending across the machine frame, this latter arm having a follower roller 72 at its upper end engageable with a cam 73 secured to the main shaft. During the motion of the main shaft, the cam 73 engages the follower roller 72 and, through the arm 70, link 69 and forward arms 67, appropriately moves the transverse bar 38 and the die blocks 19 engageable therewith in a forward direction. A low peripheral area 73a in the cam permits the springs 33 to shift the die blocks 19 and bar 38 rearwardly.

As stated above, alternate perforations may be notched, whereupon the entire carriage 24, with the die blocks 19 and punches 21 mounted there-

on, are shifted transversely of the machine a distance equal to the pitch between perforations 12. Such positioning and shifting of the carriage 24 is effected by providing an inclined cam slot 74 in one of the carriage extensions 26 engageable by a roller 75 mounted on a slide 76, guided for reciprocation along the side frame 16 of the machine by studs or pins 77 fixed to the frame and slidable within horizontal guide slots 78. The slide 76 has a pair of spaced, vertically arranged arms 79, 80 whose opposed vertical surfaces are engageable at proper sequences in the cycle of operation of the machine by a stud or follower roller 81 mounted on the end of a lever arm 82 fixed to the main shaft 63 of the machine. When the stud 81 engages the forward arm 79, the roller 75 is positioned in the cam slot 74 to hold the carriage 24 to the left of the machine (as seen in Fig. 1). Rotation of the lever 82 with the main shaft 63 until the lever engages the other vertical arm 80 will effect rearward shifting of the slide 76 and positioning of the carriage 24 to the right (as seen in Fig. 1), shifting the die blocks 19 and their punches 21 a distance equivalent to the distance between perforation centers in the outer row 12 of card perforations and also from one group of alternate selector member lugs 36 to the adjacent selector member lugs.

The slide 76 is held in the position to which it has been moved by the shaft 63 and lever arm 82 by a suitable detent consisting of a lever 83 mounted on a fulcrum pin 84 and having a roller 85 adapted to engage on either side of a triangular-shaped slide projection 86, the roller 85 being urged upwardly into engagement with the slide 76 and its projection 86 by a spring 87 attached to the other end of the detent lever 83 and to the frame. The slide 76 is prevented from inadvertent rearward movement upon engagement of the roller 85 with the rear side of the projection 86, and is prevented from unintentional forward movement upon engagement of the detent roller 85 with the forward side of the projection 86.

The punches 21 are rocked on their pivot pins 22 toward and from the die block cavities 20 at proper times in the cycle of machine operation. Such actuation occurs as a result of downward and upward movement of a bail shaft 88 extending across all of the punches and positioned within their horizontal slots 89 (see Fig. 3). The ends of the bail shaft 88 are connected to opposed arms 90 mounted on a shaft 91 extending across the machine. One of the lever arms 90 has an arm extension 92 projecting rearwardly from the shaft 91 and mounting a follower roller 93 on its rearward end rideable upon a cam 94 fixed to the main shaft 63 of the machine and upon its radial cam lobe 95 for actuating the punch 21 in an upward and downward direction. As explained below, each punch 21 is actuated twice during each cycle of the machine operation.

The main shaft 63 of the machine may be rotated in both counter-clockwise and clockwise directions by any suitable means, either manually or by a motor (not shown). The main shaft extends from the frame of the machine where an operating handle 96 is suitably secured thereon. This handle is moved forwardly against the action of a spring 97 attached to the frame and to a lever arm 98 secured on the main shaft 63, the spring serving to move the shaft 63 back to its initial position, as determined by engagement of the lever 98 with a stop or limit pin 99 mounted on the side frame 17 of the machine. Forward movement of the main shaft is also limited by engage-

ment of the lever 98 with another stop pin 100. Actually the shaft 63 is rotatable through about 90°, in accordance with the specific design shown in the drawings.

At the start of the operation of the keypunch machine, the transverse bar 38 is in a forward direction, holding all of the die blocks 19 and punches 21 in their extreme forward positions. The keys 37 are appropriately depressed in the keyboard in order to preselect all of the desired fields 11 on the card 10 to be notched, the sliding members 41 being moved by the depressed key stems 39 to appropriately position the lugs 36. Let it be assumed that the number "39" is to be notched along the marginal portions of a card 10 placed on the table 18 of the machine. The number "3" key in one column is depressed and also the number "9" key in the next adjacent column. Depression of the number "3" key moves the number "1" slide 41a and the number "2" slide 41b forwardly to shift their lugs 36a, 36b to the B position. Depression of the number "9" key in the next key column moves the number "2" slide 41b for that column forwardly to place its lugs 36b in the B position and moves the lowermost slide 41c forwardly to its extreme position to place its lug 36c in the A position. The keys and slides are held in such position by the lock slide cams 47 engaging over the pins 46 projecting from the key stems 39.

During the initial movement of the operating and main shaft 63 in a forward direction, the bar 38 is shifted rearwardly by the springs 33 attached to the die blocks 19, because of the rotation of the cam 73 to permit the roller 72 to move inwardly into the smaller diameter cam portion 73a. This rearward movement of the die blocks 19 and their associated punches 21 is limited by engagement of the rearward extension 31 of each die block with an associated lug 36. As indicated in Fig. 7, the number "1" lug 36a is engaging the number "1" punch die 19 in the first column in which the number "3" key has been depressed, and the next adjacent punch die 19 has engaged the number "2" lug 36b in the next adjacent key column. It is to be noted that the punch dies are engaging only alternate lugs across the machine, there being no die engagement with the number "2" lug 36b in the first column or the number "7" lug 36c in the second column.

The detent 83, 85 is maintaining the slide 76 in its forward position to hold the carriage 24 in its left position, and thus hold all of the punches 21 and die blocks 19 in their left positions. As the motion of the main shaft 63 continues upon forward operation of the hand lever 96, the cam lobe 95 on the punch cam 94 engages the lever 92 and moves the bail shaft 88 downwardly to move all of the punches 21 toward the die cavities 20. However, since only the number "1" punch and the associated number "2" punch referred to above have been positioned by their lugs 36a, 36b in punching relation with respect to the card 10, only those two punch members move downwardly to punch the card in adjacent fields by removing the card stock to the number "1" and number "2" perforations, respectively. As the forward movement of the main shaft 63 under the influence of the operating lever 96 continues, the cam lobe 95 rides off the follower 93 and allows the spring 101, attached to the lever 92, to move the punches 21 upwardly out of the card 10. The large periphery of the transverse bar actuating cam 73 again comes into play to engage the roller 72 and again move the bar 38 forwardly to shift

all of the die blocks 19 and punches 21 in a forward direction, the lever arm stud 81 then engaging the rearward arm 80 to effect shifting of the slide 76 to the rear and movement of the carriage 24 to the right a distance equal to the pitch between card perforations, placing the punch dies 19 in alignment with the next adjacent selector lugs 36 (see Fig. 8).

The operating lever 96 and associated main shaft 63 then begin their return motion under the influence of the return spring 97. The small diameter portion 73a of the bar actuating cam 73 is again positioned adjacent the roller 72, which permits the springs 33 to reposition the die blocks 19 and punches 21 rearwardly to limits determined by engagement of the rearward die block extensions 31 with the lugs 36. From an inspection of Fig. 8, it will be evident that the punch dies 19 have been shifted a distance equal to that between adjacent perforations 12 and that the rearward extension 31 on one die has engaged the number "2" lug 36b in the first column, which is at the B position, while the adjacent punch die has engaged the lug 36c in the next column corresponding to the C position, which is the position determined by the number "7" slide 41c which has been shifted forwardly by the number "9" key.

As the shaft 63 continues its rearward motion, the cam lobe 95 again engages the follower roller 93 on the punch bail operating arm 92 and again moves the punches 21 downwardly to notch the number "2" perforation in the first field and the number "7" perforation in the next adjacent field. The continued movement of the operating lever 96 and shaft 63 in the rearward direction again causes the cam lobe 95 to ride off the punch follower roller 93 and allows the return spring 101 to re-elevate all of the punches 21. During the last portion of the return movement of the shaft 63, the stud 61 on the latching disk 62 engages the lug 60 recess on the link 58 and moves the lock bail 54 rearwardly, to shift all lock slides 48 rearwardly and move their cams 47 off the cooperable pins 46, allowing the return springs 53 to re-elevate the keys 37 and key stems 39. As aforementioned, continued movement of the link 58 in a rearward direction causes its cam 65 to engage the fixed stud 86 and removes the lug recess 60 from engagement with the stud 61, permitting the return spring 53 to move the link 58 forwardly and allow the slide springs 52 to shift the lock slides 48 forwardly to a position wherein they may again lock depressed key stems 39 in position. During the last portion of the return movement of the main shaft 63, the carriage 24 is again shifted to the left by engagement of the lever arm stud 81 with the forward slide arm 79 and the bar 38 shifted forwardly to move all dies 19 and punches 21 forwardly. The machine is now at its initial position for appropriately punching another card in accordance with the selections of the keyboard.

Attention is directed to the Fig. 10 time chart, representing the cyclic relationships between the positions and operations of the lever 96, main shaft 63, keys 37, carriage 24, bar 38 and ball shaft 88. This chart is believed to be self-explanatory.

It is to be particularly noted that only alternate perforations along the margins of the card are subject to notching during the forward movement of the main shaft 63 and that the intervening perforations are subject to notching during the return motion of the operating shaft. In view of

the fact that adjacent perforations need not be notched simultaneously, it is possible to employ punches 21 having a width equal to the distance between perforations in any card row 12, and, for that matter, the punch width may be made actually greater than this pitch distance. As a result, the notching of adjacent perforations, as for example in notching for number "3" or number "9" in the example indicated above, effects a complete removal of the card stock and does not allow an objectionable sliver to be produced as in prior devices. This is also true in the notching of perforations in adjacent fields, as indicated by the notching of the number "1" perforation in the first field and in the deep notching of the number "7" perforation in the next adjacent field, in the example above cited.

It is also apparent that the notching of alternate perforations requires the employment of only about one-half the number of punches. The marginal fields of the card to be notched are preselected on the keyboard, and the appropriate punchings of the desired fields takes place during both the forward and rearward rotating motion of the main shaft under the influence of the handle or a motor mechanism (not shown).

While I have shown a preferred form of a machine for practicing my invention, it is to be understood that various changes may be made in its construction by those skilled in the art without departing from the spirit of the invention as defined in the appended claims.

Having thus described my invention, what I claim and desire to secure by Letters Patent is:

35 1. Apparatus for notching a card or the like provided with perforations disposed in parallel adjacency to its edge comprising a support for such card, punch and die means, key operated means for selectively determining the positioning of said punch and die means with respect to the perforations of a card on said support, means for actuating said punch and die means to notch a card on said support to selected perforations, and means for relatively shifting said punch and die means and said support a distance substantially equaling the center to center distance between adjacent card perforations.

50 2. Apparatus for notching a card or the like provided with perforations disposed in parallel adjacency to its edge comprising a support for such card, a plurality of punches along said support, each punch having a width at least equal to the center to center distance between adjacent card perforations, means for selectively determining the positions of said punches with respect to the perforations of a card on said support, means for actuating said punches to notch a card on said support to selected perforations, and means for shifting said punches along said support a distance substantially equaling the center to center distance between adjacent card perforations.

55 3. Apparatus for notching a card or the like provided with perforations disposed in parallel adjacency to its edge comprising a support for such card, a carriage having a plurality of punches mounted thereon, each punch having a width at least equal to the center to center distance between adjacent card perforations, means for selectively determining the positions of said punches with respect to the perforations of a card on said support, means for actuating said punches to notch a card on said support to selected perforations, and means for shifting said carriage parallel to said card edge to move said punches along the edge of said card a distance substantially

equaling the center to center distance between adjacent card perforations.

4. Apparatus for notching a card or the like provided with perforations disposed in parallel adjacency to its edge comprising a support for such card, a carriage having a plurality of punches mounted thereon, means for selectively determining the positions of said punches perpendicular to the edge of a card on said support, means for actuating said punches to notch a card on said support to selected perforations, and means for shifting said carriage along a line parallel to said card edge a distance substantially equaling the center to center distance between adjacent card perforations.

5. Apparatus for notching a card or the like provided with perforations disposed in parallel adjacency to its edge comprising a support for such card, punch and die means, key operated means for preselectively determining the positioning of said punch and die means with respect to the perforations of a card on said support, means for actuating said punch and die means to notch a card on said support to some of the selected perforations predetermined by said key operated means, and means for relatively shifting said punch and die means and said support a predetermined distance to enable said actuating means to notch said card on said support to the remaining selected perforations determined by said key operated means.

6. Apparatus for punching a card or the like comprising a support for such card, a plurality of punches along said support, a plurality of selector means for determining the positions of said punches with respect to a card on said support, means for relatively shifting said selector means and punches to place said punches in selected positions as determined by one group of selector means intermediately disposed with respect to a second group of selector means, and means for actuating said punches to punch a card on said support in accordance with the determinations of said one group of selector means and then in accordance with the determinations of said second group of selector means.

7. Apparatus for punching a card or the like comprising a support for such card, a plurality of punches along said support, a plurality of selector means for determining the positions of said punches with respect to a card on said support, said punches being less in number than said selector means and being adapted for simultaneous selection by only one of several groups of selector means intermediately disposed with respect to each other, means for actuating said punches to punch a card on said support in accordance with the determinations of first one group of selector means and then in accordance with the determinations of another group of selector means, and means for relatively shifting said selector means and punches from selected positions as determined by said one group of selector means to selected positions as determined by said another group of selector means.

8. Apparatus for punching a card or the like comprising a support for such card, a plurality of punches along said support, a plurality of selector means for determining the positions of said punches with respect to a card on said support, said punches being adapted for simultaneous selection by only one of several groups of selector means intermediately disposed with respect to each other, means for actuating said punches to punch a card on said support in accordance

with the determinations of first one group of selector means and then in accordance with the determinations of another group of selector means, and means operable in timed relation to said actuating means for relatively shifting said selector means and punches from selected positions as determined by said one group of selector means to selected positions as determined by said another group of selector means.

10. 9. Apparatus for notching a card or the like provided with perforations disposed in parallel adjacency to its edge comprising a support for such card, a plurality of punches along said support, a plurality of selector means for determining the positions of said punches with respect to a card on said support, the number of said punches being substantially one-half the number of said selector means and said punches being arranged for selectively and simultaneously notching only alternate card perforations as determined by one group of selector means alternately disposed with respect to a second group of selector means, means for actuating said punches to notch said card in accordance with the determinations of said first group of selector means and then in accordance with the determinations of said second group of selector means, and means for shifting said punches between operative relation with said first group of selector means and operative relation with said second group of selector means.

10. 10. Apparatus for notching a card or the like provided with perforations disposed in parallel adjacency to its edge comprising a support for such card, a plurality of punches along said support, each punch having a width at least equal to the center to center distance between adjacent card perforations, a plurality of selector means for determining the positions of said punches with respect to a card on said support, the number of said punches being substantially one-half the number of said selector means and said punches being arranged for selectively and simultaneously notching only alternate card perforations as determined by one group of selector means alternately disposed with respect to a second group of selector means, means for actuating said punches to notch said card in accordance with the determinations of said first group of selector means and then in accordance with the determinations of said second group of selector means, and means for shifting said punches between operative relation with said first group of selector means and operative relation with said second group of selector means.

11. 11. Apparatus for punching a card or the like comprising a support for such card, a carriage having a plurality of punches mounted thereon perpendicular to an edge of a card on said support, a plurality of selector means for determining the positions of said punches with respect to a card on said card support, said punches being adapted for simultaneous selection by only one of several groups of selector means intermediately disposed with respect to each other, means for actuating said punches to punch a card on said support in accordance with the determinations of first one group of selector means and then in accordance with the determinations of another group of selector means, and means operable in timed relation to said actuating means for shifting said carriage along said selector means to move said punches from operative relation with one group of said selector means to

operative relation with said another group of selector means.

12. Apparatus for notching a card or the like provided with perforations disposed in parallel adjacency to its edge comprising a support for such card, a carriage having a plurality of punches mounted thereon, means for selectively determining the positions of said punches with respect to the perforations of a card on said support, and common means for actuating said punches to notch a card on said support and for shifting said carriage along a line parallel to said card edge a distance substantially equaling the center to center distance between adjacent card perforations.

13. Apparatus for punching a card or the like comprising a support for such card, a carriage having a plurality of punch means mounted thereon for movement perpendicular to an edge of a card on said support, a plurality of key operated means movable perpendicularly to an edge of said card, alternate key operated means being engageable with said punch means for selectively positioning them with respect to a card on said support, means for actuating said punch means to punch said card, and means for shifting said carriage across the lines of movement of said key operated means to move said punch means from engagement with said alternate key operated means to the adjacent key operated means.

14. Apparatus for punching a card or the like comprising a support for such card, a carriage having a plurality of punch means mounted thereon for movement perpendicular to an edge of a card on said support, a plurality of key operated means movable perpendicularly to an edge of said card, alternate key operated means being alignable an engageable with said punch means for selectively positioning them with respect to a card on said support, means for actuating said punch means to punch said card, means for shifting said punch means from engagement with said alternate key operated means, and means for shifting said carriage across the lines of movement of said key operated means to move said punch means from alignment with said alternate key operated means to alignment with the adjacent key operated means.

15. Apparatus for punching a card or the like comprising a support for such card, a carriage having a plurality of punch means mounted thereon, a bank of keys arranged in columns, a plurality of selector means adapted to be actuated by selected keys in said columns for pre-selecting the punch means for punching said card, means for placing said punch means in alignment with alternate selector means, means for actuating said punch means, and means for shifting said carriage to move said punch means from alignment with said alternate selector means to alignment with adjacent selector means.

16. Apparatus for punching a card or the like comprising a support for such card, a carriage having a plurality of punch means mounted thereon, a bank of keys arranged in columns, a plurality of selector means adapted to be actuated by selected keys in said columns for pre-selecting the punch means for punching said card, means for placing said punch means in alignment with alternate selector means, means for shifting said carriage to move said punch means from alignment with said alternate selector means into alignment with adjacent se-

lector means, and means for actuating said punch means before and after shifting of said carriage.

17. Apparatus for punching a card or the like comprising a support for such card, a carriage having a plurality of punch means mounted thereon, a plurality of selector means for selecting punch means for punching said card, means for placing said punch means in operative relation with alternate selector means, means for shifting said carriage to move said punch means from operative relation with said alternate selector means into operative relation with adjacent selector means, and means for actuating said punch means before and after shifting of said carriage.

18. Apparatus for punching a card or the like comprising a support for such card, a carriage having a plurality of punch means mounted thereon, a plurality of selector means for selecting punch means for punching said card, means for placing said punch means in operative relation with alternate selector means, means for shifting said carriage to move said punch means from operative relation with said alternate selector means into operative relation with adjacent selector means, means for actuating said punch means before and after shifting of said carriage, and common means for operating said placing means, shifting means and actuating means.

19. Apparatus for notching a card or the like provided with perforations disposed in parallel adjacency to its edge comprising a support for such card, a carriage having a plurality of punches mounted thereon for movement perpendicular to said card edge, a bank of keys arranged in columns, a plurality of selector means adapted to be actuated by selected keys in said columns and movable perpendicularly to an edge of said card for preselecting the punches for punching said card, means for placing said punches in alignment with alternate selector means, means for shifting said carriage along a line parallel to said card edge to move said punches from alignment with said alternate selector means into alignment with adjacent selector means, and means for actuating said punches before and after shifting of said carriage.

20. Apparatus for notching a card or the like provided with perforations disposed in parallel adjacency to its edge comprising a support for such card, a carriage having a plurality of punches mounted thereon for movement perpendicular to said card edge, each of said punches having a width at least equal to the center to center distance between adjacent card perforations, a bank of keys arranged in columns, a plurality of selector means adapted to be actuated by selected keys in said columns and movable perpendicularly to an edge of said card for preselecting the punches for punching said card, means for positioning said carriage to place said punches in alignment with alternate selector means, means for shifting said carriage along a line parallel to said card edge a distance equaling the center to center distance between adjacent card perforations in order to move said punches from alignment with said alternate selector means into alignment with intervening selector means, means for actuating said punches before and after shifting of said carriage, and common means for operating said positioning means, shifting means and actuating means.
